UNITED STATES PATENT OFFICE.

CHRISTIAN AALBORG, OF WILKINSBURG, PENNSYLVANIA, ASSIGNOR TO WESTINGHOUSE ELECTRIC AND MANUFACTURING COMPANY, A CORPORATION OF PENNSYLVANIA.

OSCILLATING FAN.

1,241,600.

Specification of Letters Patent.

Patented Oct. 2, 1917.

Application filed December 26, 1911. Serial No. 667,922.

To all whom it may concern:

Be it known that I, CHRISTIAN AALBORG, a citizen of the United States, and a resident of Wilkinsburg, in the county of Allegheny and State of Pennsylvania, have invented a new and useful Improvement in Oscillating Fans, of which the following is a specification.

My invention relates to oscillating fans, and it has special reference to air-operated devices of this type which are provided with obstructing vanes for the purpose of effecting the oscillatory movements of the fan.

One object of my invention is to provide a device of the above-indicated character which shall be simple, light and durable in construction and efficient in operation, and shall embody means that will permit of desk or wall mounting and adjustments of position without interfering with normal operation.

Another object of my invention is to provide adequate means for reversing the position of the obstructing vanes as the fan approaches its respective limits of travel, thereby effecting a retardation in the speed of oscillation just prior to engagement with the limiting stops.

In the past, the field of usefulness of air-controlled oscillating fans has been somewhat restricted for the reason that provision has not been made for adjustability of mounting, and the reversing mechanism for operating the vanes has been associated with the supporting base. Furthermore, it has been customary to operate fans at full speed throughout the entire range of travel, which resulted in a considerable shock or jolt when engagement with the limiting stops occurred. Thus, the entire mechanism was subjected to undue wear and severe strains which often resulted in damage to the apparatus.

According to my present invention, I propose to overcome the difficulties herein-

before recited, and to provide a readily adjustable air-controlled oscillating fan which is easily reversed in direction without undue strain on the mechanism.

In the accompanying drawings, Figure 1 is a view in side elevation of a device constructed in accordance with my invention; Fig. 2 is a plan view, partially in section, of a portion of the device shown in Fig. 1; 55 Figs. 3 and 4 are, respectively, a sectional view and a view in side elevation of a portion of the structure shown in Fig. 2; and Figs. 5 and 6 are views similar to Fig. 2, showing the relative positions of certain 60 portions of the apparatus during its operation.

Referring to the drawings in detail, a motor 1 of any well-known construction is pivotally mounted upon a supporting base 65 2 by means of an adjustable hinge or coupling 3, that permits of wall mounting, as shown in full lines in Fig. 1, or of desk mounting, as outlined in dot and dash lines in said figure.

The shaft 4 of the motor 1 is provided with a plurality of fan blades 5 which are protected from contact with exterior objects by a cage or guard 6, in the usual manner.

A shaft 7 is mounted in suitable bearings 8 and 9 in front of the fan blades 5, and is centrally disposed with respect to the shaft 4 and at right angles thereto. The upper bearing 8 is associated with a projecting 80 member 10 which forms a part of the protecting guard 6, while the lower bearing 9 is carried at the outer end 11 of a supporting bracket 12, which is rigidly suspended from and attached to a projecting 85 arm 13 by rivets or screws 14. The projecting arm 13 constitutes a part of a main bearing member 15 that is secured to motor 1 in a suitable manner.

A plurality of obstructing vanes 17, 18, 90 19 and 20 are associated in pairs that are respectively attached to the shaft 7 above

and below the motor shaft 4, the coöperating vanes of each pair having a definite angular relation, the one to the other.

Attached to the lower end of the shaft 7, and located above the bearing 9, is a gear segment 22 which is adapted to coöperatively engage a plurality of teeth 23, the latter being located at the free outer end of an operating lever 24, which is secured to a shaft 25 and is adapted for limited rotative movement between a pair of stops 26 and 27 upon the supporting bracket 12. The lever 24 projects through an opening 28 in the supporting bracket 12, and the shaft 25, to which said lever 24 is riveted, is mounted between projecting portions 29 and 30 which form integral parts of the bracket member 12.

A cam member 31 is rigidly secured to the inner end of the lever 24, and is adapted for coöperative engagement with a relatively stationary member or stop 34. The cam member 31 is symmetrically shaped and is provided with a plurality of substantially oppositely projecting arms 35 and 36, the curved cam surfaces being provided with projections 38 for a purpose to be hereinafter set forth.

The coöperating stop 34 is mounted upon a projecting member 39 which forms an integral part of a main bearing member 40, the latter member being stationary with respect to the pivotally mounted motor 1, and independently adjustable in position as regards the supporting base 2.

The motor 1 is pivotally mounted in the bearing member 40 by means of a pin 41, which constitutes a part of the bearing member 15 and projects into a recess provided in the bearing member 40. Interposed between the bearing members 15 and 40, is a floating collar member 42 which is provided with an upwardly projecting portion 43 and a plurality of downwardly projecting portions 44 and 45, all of said projecting portions being located exteriorly with respect to the bearing members 15 and 40. The upwardly projecting portion 43 is provided with an elongated slot 46, while the downwardly projecting portions 44 and 45 are adapted to engage a portion of the projecting member 39 when the fan approaches its limits of travel.

The bearing member 15 is also provided with an annular recess 47 for the purpose of receiving an annular spring 50 which surrounds the pin 41 and the ends of which project through a slotted opening 51 in the side of said bearing member and also through the slot 46 in the floating collar member 42. By means of the structure just described, the oscillatory movement of the fan is limited to a definite range of travel, and resilient means, in the form of the spring 50, is pro-

vided for arresting the movement thereof 65 at the respective limits of travel.

Assuming that the various parts of the device occupy the positions shown in Figs. 1 and 2, the operation thereof is as follows:

A portion of the current of air produced 70 by the rotating fan blades 5, is directed against the inner faces of the obstructing vanes 18 and 20, whereby a movement of the fan in a clock-wise direction is effected in a well known manner. When the fan approaches the limit of its travel in a clock-wise direction, the projecting portion 38 of the cam surface of arm 35 comes into co-operative engagement with the pin or stop 34, whereby the operating lever 24 is actuated to reverse the positions of the obstructing vanes 17, 18, 19 and 20, by reason of the coöperative engagement of the teeth 23 and the gear segment 22.

During this period, the floating collar 85 member 42 is rotated in a clock-wise direction by reason of its engagement with the spring 50 which is also in contact with the bearing member 15.

The relationship and proportions of the various component parts are such that the downwardly projecting portion 45 of the floating collar member 42 engages the projecting portion 39 at approximately the time the cam member 31 effects a reversal of the 95 obstructing vanes by reason of its engagement with the pin 34.

Having effected a reversal in position of the obstructing vanes 17 to 20, inclusive, 100 the air delivered by the fan is directed against the inner faces of the vanes 17 and 19, whereby the rotative movement of the fan in a clock-wise direction, is retarded or cushioned as the fan approaches its limit of travel. By thus retarding the movement of 105 the fan just prior to its engagement with its limiting stops, it is apparent that undue shocks and strains to which it would otherwise be subjected, are prevented.

Subsequent to the reversal of the obstructing vanes, the fan travels a short distance and, in so doing, is opposed by the action of the spring 50, so that its motion is finally arrested thereby, the various parts occupying 115 the positions shown in Fig. 6.

Having reached its limit of travel in a clock-wise direction, and inasmuch as the obstructing vanes 17 and 19 are acted upon by the air from the rotating blades 5, a reversal in the direction of rotation of the fan is effected, and this movement continues until the projection 38 of the arm 36 of the cam member 31 comes into engagement with the pin 34, and thereby causes a reversal of the obstructing vanes 17 to 20, inclusive, in a manner similar to that hereinbefore described.

It is not considered necessary to further

describe the operation of this device on account of its similarity to that portion of the operation which has just been set forth, and it is believed that those skilled in the art will 5 have no difficulty in understanding that a periodic oscillating movement of the fan is obtained. Obviously, by properly designing the cam surface of the member 31, a reversal of the obstructing vanes 17 to 20, inclusive, 10 may be effected at any predetermined point with respect to the limits of travel, and, if desired, the vanes alone may be employed for retarding the movement of the fan and reversing its direction of rotation without 15 the use of limiting stops of any character whatever.

Moreover, inasmuch as the reversing mechanism is located above the hinge or coupling 3 and is entirely independent of 20 the supporting base 2, the device may be mounted and adjusted in any desired manner, which is a distinct advance over the prior art.

I do not wish to be restricted to the specific 25 structural details and the arrangement and location of parts hereinbefore set forth, and I desire that only such limitations shall be imposed as are indicated in the appended claims.

30 I claim as my invention:

1. The combination with a pivotally mounted motor-driven fan, movable vanes associated therewith for effecting an oscillatory movement thereof, and means for limiting 35 the travel thereof, of means for completely reversing said vanes a predetermined interval prior to the operation of said limiting means.

2. The combination with a pivotally mounted motor-driven fan, movable vanes associated therewith for effecting an oscillatory movement thereof, and means for limiting the travel thereof, of means independent of said limiting means for actuating 45 said vanes a predetermined time before the operation of said limiting means.

3. The combination with a pivotally mounted fan, movable vanes associated therewith for effecting oscillatory movements thereof, and means for limiting the travel of said fan, of means for completely reversing said vanes to retard the movement of said fan a predetermined interval prior to the action of said limiting means.

55 4. The combination with a pivotally mounted fan, having an adjustable supporting base, and movable vanes for effecting an oscillatory movement of said fan, of means independent of said base for causing said vanes to retard the movement of said fan as it approaches its limits of travel.

5. The combination with a pivotally mounted fan, movable vanes associated therewith for effecting an oscillatory move-

ment thereof, and an adjustable supporting 65 base, of means for limiting the travel of said fan and means for reversing the position of said vanes prior to the ends of travel, both of said means being independent of said supporting base.

6. In an oscillating fan, the combination with obstructing vanes movably associated therewith for effecting oscillatory movements thereof, of means dependent upon the oscillations of said fan for completely reversing its vanes a predetermined distance 75 ahead of its limits of travel.

7. In an oscillating fan, the combination with an adjustable supporting base adapted for desk or wall mounting, and movable 80 vanes disposed in front of said fan for effecting oscillatory movements thereof, of means independent of said supporting base and dependent upon the oscillations for periodically actuating said vanes in opposite 85 directions.

8. In an oscillating fan, the combination with an adjustable supporting base adapted for desk or wall mounting, movable obstructing vanes disposed in front of said 90 fan and adapted for limited movement, and means for limiting the oscillatory movement of said fan, of mechanical means independent of said limiting means and dependent upon the oscillations of said fan for reversing the position of said vanes before the 95 end of travel is reached.

9. The combination with a rotatable, pivotally mounted motor-driven fan and a set of movable vanes associated therewith 100 for effecting oscillatory movements thereof, of an engaging member, a coöperating cam member, and mechanical means for effecting changes in the position of said set of vanes, the contour of said cam being such as to reverse the position of said vanes before the 105 limits of travel are reached.

10. The combination with a pivotally mounted motor - driven fan, obstructing vanes associated therewith for effecting oscillatory movements thereof, and a single yielding means for arresting the movement of said fan in either direction, of means embodying a relatively movable cam and coöperating member for reversing said vanes 110 prior to the operation of said yielding means.

11. The combination with a pivotally mounted fan, and adjustable vanes for oscillating said fan within a definite range 115 of travel, of a pivotally mounted lever associated with said fan and coöperating with said vanes, a symmetrically shaped cam fixed to said lever, and a stationary member adapted to be engaged by said cam in both 120 directions of travel, whereby said vanes are reversed before the limits of travel are 125 reached.

4
12. The combination with a pivotally mounted motor-driven fan, movable vanes associated therewith for effecting an oscillatory movement thereof, and an adjustable supporting base, of a single yielding means disposed above said base for retarding the movement of said fan at the ends of its travel, and means coöperating with a portion above said base and independent of said

limiting means for reversing the positions 10 of said vanes.

In testimony whereof, I have hereunto subscribed my name this 12th day of Dec., 1911.

CHRISTIAN AALBORG.
